BURNER ASSEMBLY FOR FLOW-TYPE GAS GENERATORS

William P. Gee, Plainfield, N. J., assignor to Texaco Development Corporation, New York, N. Y., a corporation of Delaware

Application September 20, 1951, Serial No. 247,425

5 Claims. (Cl. 158—104)

This invention relates to fluid fuel burners and more particularly to fluid fuel burners of the kind used in flow-type gas generators. The latter are essentially closed reaction chambers, housing burners, and are primarily used for the partial combustion of gaseous or vaporized liquid hydrocarbons in the manufacture of synthesis gases.

For illustrative purposes, the apparatus of the invention shown on the attached drawings is for use as a conversion burner, for partial combustion of methane to form carbon monoxide and hydrogen. This reaction is well known to the art, and in general is represented by the following formula:

Obviously, other reactants could be used in burners of this type, and this particular reaction only typifies such processes.

The reaction temperatures experienced in this conversion process are of the order of 2600° F., and one of the biggest problems encountered is one of providing adequate cooling for the burner elements to prevent their deterioration at these temperatures.

It is the primary object of this invention to provide a burner structure for a flow-type gas generator with adequate cooling means to permit satisfactory burner operation over substantial time periods.

It is a further object of this invention to provide a burner assembly in which the individual burner elements and the cooling means therefor, form an integral unit which can easily be inserted in and removed from a flow-type gas generator.

Other objects of this invention will be apparent from the following description and read in conjunction with the attached drawing in which,

Figure 1 is a side elevation, partly in section, of a burner assembly embodying the principles of this invention.

Figure 2 is a side elevation, partly in section, of one of the burner elements.

Figure 3 is a top plan view of the burner assembly showing a preferred burner element arrangement, and

Figure 4 is a side elevation, partly in section, of a flow-type gas generator showing the burner apparatus of this invention inserted therein.

Referring first to Figure 2, each individual burner element comprises an outer tube 10 and inner tube 11 concentrically arranged, the inner tube being spaced from the outer by a member 12 having ports 13 extending therethrough. The reactant gases, for example methane and oxygen, are fed to the burner elements through a conduit 14 communicating with the annular space between 10 and 11 and directly through tube 11, respectively.

Referring now to Figure 1, this shows the individual burner elements of Figure 2 mounted in a cooling jacket 15. While this member is shown as being annular in form, it could also assume a variety of plane figure shapes without materially affecting the operation. In addition, the jacket member may be made up of a relatively large number of segments to obviate any difficulty caused by expansion of the heated metal. The upper and lower walls 16 and 17 of the jacket member 15 are bored and threaded to receive the individual burner elements, the latter having mating projecting threaded flanges 18 and 19. The individual burner ele-

ments may thus be rigidly affixed to the cooling member in fluid tight relation thereto.

The cooling jacket 15 is provided with inlet and outlet connections 20 and 21 for circulation of a coolant, such as water, interiorly thereof. In this fashion the circulating coolant fills the cooling jacket and substantially completely surrounds each individual burner element. By maintaining a high rate of flow of the coolant, each burner element and the cooling jacket itself is cooled by direct heat exchange relation with the circulating coolant. In this manner, the burner elements are maintained at a sufficiently low temperature to prevent or substantially retard their deterioration.

The individual burner elements may be conveniently arranged in a concentric circular pattern substantially as shown in Figure 3. The burner tips which are exposed directly to the heat of the combustion space are made nearly flush with the upper wall 16 of the cooling jacket 15. Corresponding tubular passageways of the individual burner elements may be linked by manifold members 22, 23 for supplying the reactant fluids to the burners. Figure 4 shows such an arrangement with the entire assembly mounted in a flow-type gas generator 24. Only a single row of burners and manifold connections is shown to simplify the drawing.

The generator is provided with an outlet 25 for the reaction products which, in accordance with standard practice, may be led to a waste heat boiler wherein the heat would be utilized to generate steam. While flow-type gas generators are well known to the art, it may be pointed out that the combustion space 26 is surrounded by a layer of refractory material 27 to withstand the intense heat generated in partial combustion processes of the type referred to herein.

I claim:

1. A burner assembly for use in a flow-type gas generator comprising: a closed hollow metallic cooling jacket member comprising spaced, substantially parallel upper and lower walls; a plurality of plural-passage burner elements mounted in and extending through said walls a major portion of the outer walls of said burner elements being thus disposed within the space defined by the walls of said cooling jacket member; a coolant inlet and outlet means mounted on and communicating with the interior of said member so that each of said burner elements is substantially uniformly cooled by direct contact with the coolant; and means including closed conduits connected to said burner elements for supplying reactant fluids thereto.

2. A burner assembly for use in a flow-type gas generator comprising: an annular, hollow metallic cooling jacket member; a plurality of concentric tubular burner elements mounted in and extending through opposite walls of said member a major portion of the outer walls of said burner elements being thus disposed within the space defined by the walls of said cooling jacket member; closed conduit means connecting corresponding burner element tubes for supplying reactant fluids thereto; and means affording circulation of fluid coolant within said jacket member in contact with each outer wall of said burner elements to cool the burner assembly.

3. A burner assembly as defined by claim 1 in which the burner element tips are substantially flush with a wall of said cooling jacket.

4. A burner assembly as defined by claim 2 in which the burner elements are arranged in a concentric circular pattern in said cooling jacket.

5. A burner assembly as defined by claim 1 in which the burner elements comprise a pair of concentric tubular members, the outer of which members include threaded flanges at opposite ends thereof for attachment to opposite walls of said cooling jacket member.
